UNITED STATES PATENT OFFICE

JOSEPH V. HULL, OF BROOKLYN, NEW YORK, ASSIGNOR, BY MESNE ASSIGNMENTS, TO ANCHOR CAP & CLOSURE CORPORATION, OF NEW YORK, N. Y., A CORPORATION OF NEW YORK.

MACHINE FOR VACUUM-SEALING.

1,134,065.

Specification of Letters Patent. Patented Mar. 30, 1915.

Application filed March 6, 1912. Serial No. 682,051.

To all whom it may concern:

Be it known that I, JOSEPH V. HULL, a citizen of the United States, and a resident of Brooklyn, in the county of Kings and State of New York, have invented a new and useful Improvement in Machines for Vacuum-Sealing, of which the following is a specification.

My invention relates to improvements in machines for vacuum sealing and mechanically sealing of bottles, jars, cans, and other receptacles provided with caps or like closures.

The machine is especially adapted for the sealing of glass bottles, glass jars and other glass receptacles provided with caps having an annular beading which is compressed vertically so as to compress a packing ring within the beading, and at the same time squeeze a portion of the packing ring out of the beading and against the outer face of the bottle, jar or other receptacle so as to form a mechanical seal.

The invention hereinafter described is shown in the drawings in which—

Figure 1 represents a side view of the machine. Fig. 2 a view from the opposite side partly in section. Fig. 3 a front view. Fig. 4 a sectional view of the upper part of Fig. 2. Fig. 5 a sectional view of the mechanical sealing mechanism at the end of the sealing operation. Figs. 6, 7, 9, 10, 11 and 12 detailed sectional views of parts of the apparatus more particularly described hereinafter. Fig. 8 is a diagrammatic section showing the principle of operation of the clutch used by me.

In the drawings in which like numbers represent like parts, 1 is a hollow frame or standard provided with a base to support the apparatus.

2, 2 are arms cast with the frame and extending therefrom.

3 is a supporting head adapted to support the chamber and mechanical sealing mechanism.

4 is a vacuum chamber provided with a door 5 which consists of inner and outer plates 7 held together by means of bolts 8, and supporting between the two plates a packing 6.

9 is an arm pivoted to the top of the door 5 at one end, and at its other end pivoted to the standard 1, the object of which is to retain the door 5 in parallel position with

the front of the vacuum chamber 4 as the door is raised and brought into position to close the vacuum chamber. The door 5 is pivoted by pivot 17 to yoke 10 which is pivoted at 11 in the rear of the supporting frame 1. This yoke 10 at its extreme rear end is pivoted by pivot 13 to arms 12 which extend down each side of the supporting frame 1, and at their lower ends are pivoted by pivot 14 to the treadle 15, pivot 14 being located in the slot 19. It will thus be seen that by the operator pressing downward upon the treadle 15 the door 5 will be closed through the medium of arms 12 and yoke 10, which yoke will raise the door 5 up and inward until it comes in contact with the front of the vacuum chamber, when a continued pressure of the foot will cause the packing to be compressed so as to make the vacuum chamber air-tight. The treadle 15 is pivoted to the supporting frame by pivot 20 and is provided with a spring 33 adapted to hold it upward and in its normal position as shown in the drawings. This treadle, or pedal mechanism, for closing the vacuum chamber permits the operator to control the operation of the machine with his foot, so that both hands may be used to insert and withdraw packages in the vacuum chamber simultaneously, thereby greatly increasing the capacity of the machine. A further advantage is that the closing of the vacuum chamber by the operator avoids serious accident should his hand be caught by the closing wall. This is not the case in other forms of machines where power is applied to close the chamber.

The door mechanism as described operates with substantially a parallel movement. The door occupies a minimum space in its movements and as a result its operation does not interfere in any way with the operator as he moves the packages in and out of the vacuum chamber. This method of closing the chamber also permits the securing of an air-tight packing joint. In machines where the door is directly attached or hinged to the vacuum casing, the thickness of the packing must be definite and exact to a very small fraction of an inch, or a good vacuum cannot be secured in the chamber. The packing must always be maintained at this definite thickness and accordingly no great amount of wear is permissible. By the provision applicant makes of a loosely swinging

door, the thickness of the packing may be varied within wide range and yet the packing joint will always be air-tight, and this is also true in cases where the packing has become worn.

34 is a shaft mounted in a bearing in the support 30 having a gear wheel 38 keyed to it, which gear wheel meshes with the gear 31 loosely mounted on the shaft 37.

10 35 and 36 are pulley wheels mounted on the shaft 34, 35 being keyed to the shaft and 36 being an idler. I provide a clutch mechanism shown in detail in Figs. 6 and 7 so as to operatively bring the shaft 37 into engagement with the gear wheel 31. This clutch mechanism consists of a casting 24 having a slot 25 in which is located a slide bolt 26 held normally projecting out of the slot 25 by means of the spring 28 as shown 15 in Fig. 7. For clearness of description I have shown in Figs. 6 and 7 the clutch mechanism in operative position, in this respect being different from the other figures of the drawing, as in those figures the clutch 20 is not in operative position. On the gear wheel 31, I provide a series of pins 32 so arranged that the slide bolt 26 will pass between them and thus bring the gear wheel 31 into operative connection with the casting 24, and the casting 24 being keyed to the shaft 37, will thereby cause the shaft 37 to rotate. In order to disengage the clutch 25 from operative position, as shown in Figs. 6 and 7, I provide an arm 21 pivoted to the treadle 15 by a pivot 22, having at its upper end a segment with a beveled edge 23 which engages with the bevel 27 on the slide bolt 26 as the device rotates, and thereby forces the slide bolt 26 out from engagement between the pins 32, thus disengaging the clutch. The segment 23 is shown with a long cam surface in Fig. 6, the object of which is to hold the slide arm 26 out of engagement 40 sufficiently long so that the machine may 45 come to a stop. In order to facilitate the stopping, I provide a brake 39 supported by the frame 1 through the medium of the arm 40 to which the brake 39 is bolted. I preferably so time the operation of the clutch 50 that it cannot engage with the gear wheel 31 until the door 5 of the vacuum chamber has been closed.

In the arms 2, 2 is loosely mounted a slide rod 41 (see Figs. 2 and 4) which is hollow 55 at its upper end and provided with an internal ledge 45 upon which rests the disk or washer 44. Passing through the disk or washer 44 is a bolt 46 fixed to the table 42 above and bearing a nut below the washer. Between the washer and the table 42 is provided a spring 47, so as to permit the table 42 to be moved irrespective of the movement 60 of the slide rod 41. The table 42, upon which the jar or receptacle to be sealed is 65 placed, is provided with a guide 43, and has

a piece of felt or other suitable material 48 for the receptacle to rest upon. By means of this self-adjusting support, the breakage of glass containers during the capping operation is prevented, and by mounting the support within the vacuum chamber, it is 70 always movable freely under pressure of the container as no packing gland is required for the stem of the support. This construction obviates the danger of loss of vacuum 75 on the one hand, and of the support working too stiffly on the other, due to pressure of air-tight packing that would otherwise be necessary. At the lower end of the slide rod 41 a block 46^a is clamped by means of the screw 47^a, which block on its inner side is provided with an arm 51 (see Fig. 10) upon which is loosely mounted a roller 52. This roller 52 engages in a cam slot 49 in the disk 50 keyed to the shaft 37, so that as the shaft 80 37 rotates it rotates the disk 50, and the roller 52 on the arm 51 engaging in the cam groove 49 causes the slide rod 41 to be raised or lowered depending upon the position of the roller 52 in the cam groove 49. Keyed to 85 the shaft 37 are two cams 53 and 54 (see Figs. 2 and 11) which may be made in one casting, if desired. 55 is a roller loosely mounted upon the lower end of the rod 57 and engaging with the cam 54. 56 is a roller 90 loosely mounted on the rod 57 engaging with the cam 53. The rod 57 is pivoted to the rod 58. The upper end of rod 58 is pivoted to the rod 59 on the end of which is secured a washer 60 by means of the nut 66 adapted 100 to hold the spring 67 in place on the rod 59. At the lower end of the spring 67 is mounted on the rod 59 a movable yoke 62 pivoted to the lever 63 so arranged that as cam 54 causes the members 57, 58 and 59 to move 105 downward, the spring 67 will force the yoke 62 downward thus rocking the lever 63 which is pivoted to the head 3 by pivot 68, and raising the arm 65 which is pivoted to the outer end of the rocking lever 63 by pivot 110 64 to operate the mechanical sealing mechanism hereinafter described. Supported from the head 3 and held in place thereby means of the set screw 69 is the mechanical sealing mechanism and vacuum sealing chamber, 115 which consists of the casting 70 having secured to it by bolts 72 the casing 71 of the vacuum chamber. At the lower end of the casing 71 and secured to it by bolts 74 is the bottom 73 of the vacuum chamber having 120 a central opening through which the slide rod 41 passes supporting the table 42. Projecting from the bottom plate 73 of the vacuum chamber and surrounding the slide rod 41 is a flange 77 which is screw-threaded on 125 its outer surface, and is provided on its lower side with a bevel. I provide a packing nut 75 which is threaded so as to engage with the thread on flange 77. Compressed between the packing nut and the lower end of the 130

flange 77 is a packing 76 so as to make an air-tight joint between the slide rod 41 and the bottom plate of the vacuum chamber, while at the same time permitting movement of the slide rod 41.

5 My mechanical sealing device consists (see Figs. 4 and 5) of the centering head 78 having a downwardly extending flange 79. This centering head is screw-threaded so as 10 to engage with a screw-thread in the casting or head block 70 and is held against rotation by means of the spring pressed stud 80, although by reason of this stud being spring pressed, the centering cap may be rotated 15 by use of a tool, or by sufficient force being operated to rotate same in opposition to the spring, or by loosening the screw 81 which controls the pressure of the spring on the stud 80. The centering cap 20 78 is provided with an opening in which is placed a movable bar 82, which, if desired, may be a magnet. Segmental jaws 83, having a beveled shoulder 84 on their outer side and a shoulder 86 on their inner side adapted 25 to engage below a beading on the cap of the closure, are pivoted by pivots 87 to the movable head 88. The jaws 83 are normally held outward by means of spring 89. When the movable head 88 is in its normal position, as shown in Fig. 4, and the machine is 30 operated, the head moves upward, and the beveled shoulders 84 on the outside of the segmental jaws 81 engage with the bearing surface 90 held in place at the upper part 35 of the vacuum chamber, so as to force the segmental jaws in under the beading of the cap. As the movable head 88 continues to move upward it causes the shoulders 86 to compress the beading on the cap between 40 the downwardly extending flange of the centering cap 78 and the shoulders 86 on the segmental jaws 83, while the beading is at the same time prevented from enlarging its diameter by means of the inner side of the 45 segmental jaws. The chuck is shown at the end of the operation of mechanically sealing a receptacle in Fig. 5.

The movable head 88 is provided with pins 91 which engage with openings in the 50 lower end of the vertically moving rods 92. These vertically moving rods 92 operate in openings provided in the casting or cup-shaped chamber 70, which openings are screw-threaded to receive packing nuts 83, so 55 as to compress the packing 94 for the purpose of making air-tight joints, while at the same time permitting movement of the rods 92. At the upper ends these rods 92 by means of pivots 95 are operatively attached 60 rods 65, which in turn are by pivot 64 pivoted to the lever arm 63 mounted on pivot 68.

Leading from any suitable exhausting apparatus is a pipe 96 opening into the vacuum 65 chamber (see Fig. 1). In the pipe 96 near

the vacuum chamber is provided a two-way valve, as shown in Fig. 12, which when the machine is in normal position, as shown in Fig. 1, is set so that the passage 109 communicates with that part of the pipe 96 70 leading to the vacuum chamber, while the passage 108 communicates with the openings in the valve casing 110, so as to permit air to enter the vacuum chamber. When the valve is operated, as hereinafter described, the passage 107 comes into direct alinement with that part of the pipe 96 75 leading to the vacuum chamber, while the other end of the passage 107 comes in direct alinement with that part of the pipe leading 80 to the exhausting apparatus, and the two passages 108 and 109 are closed by the casing of the valve. This valve 97 is provided with a disk (see Fig. 1) to which is pivoted a rod 98, the other end of the rod 98 being pivoted to a rocking lever 99, which rocking lever is pivoted at 100 to the casing 1. The valve is kept normally open by means of a spring 101 which retains the rod 98 in normal position, as shown in Fig. 1. Mounted 90 on the pivot 102 on the other end of the rocking lever 99 is a roller 103 (see Fig. 9). The disk 50, which is keyed to the shaft 37 as heretofore described, is also provided with a cam surface 104, which extends about two-thirds around the disk, as shown in Fig. 10, and is provided at each end with a beveled surface. As the shaft 37 rotates, thereby rotating the disk 50, it also rotates the cam surface 104 until the beveled edge of the cam surface engages with the roller 103, causing it to be pressed in opposition to the spring 101 toward the rear of the machine, thus 100 raising rod 98, rotating the disk on the valve 106 97, and bringing the passage 107 in the valve in alinement with the adjoining openings in the pipe leading to the vacuum chamber and 110 to the exhausting apparatus, while at the same time closing the passages 108 and 109 115 in the valve. By reason of the timing of the clutch operating mechanism, heretofore described, so that the machine will not operate until the door 5 is closed, the valve 97 will not close until the door 5 is shut and 120 will open before the door 5 is opened. As the door 5 is raised, the upper edge comes in contact with the lower edge of the contact pin 105 and compresses the spring 107 coiled about the rod 106. In this way any sudden 125 jarring or shock to the apparatus is prevented. In the rear of the standard or casing 1, I also provide an adjustment screw or bolt 18, so arranged as to adjust the distance of movement of the yoke 10. The resilient pin 105 not only prevents jar or shock when the door is quickly closed, but it also helps to open the door quickly after the sealing operation is completed. The tendency of 130 the door to stick when the machine is oper-

ated rapidly is due in part to the slowness with which the pressure in the chamber reaches full atmospheric pressure, and this tendency is partly compensated for by the energy stored in the spring 107. This resilient power storing device is of further value as it also counterbalances in part the inertia of the door both in its opening and closing movements, and in practical effect requires less labor on the part of the operator to work the machine.

The operation of my mechanical and vacuum sealing machine is as follows: A bottle, jar or other receptacle is placed upon the table 42, being guided into its proper position by means of the guides 43. A cap provided with a downwardly extending flange having an annular beading in which is located a packing ring, although other forms of caps may be used if desired, is placed upon the receptacle or on the centering cap. The operator then presses downward upon the treadle 15, which through the medium of rods 12 and yoke lever 10 closes the door 5. As the door closes, the continued downward pressure of the treadle withdraws the segment 23 of the clutch from engagement with the slide bolt 26, permitting the slide bolt to be pressed outwardly by the spring 28, so as to pass between two of the pins 32 in the gear wheel 31. The gear wheel 31 being in mesh with the gear 38 fixed to the shaft 34, having fixed to it the pulley 35 which is being operated, the clutch 35 is caused to rotate, thereby rotating the shaft 37 to which it is keyed, and at the same time rotating cams 53, 54 and disk 50. As the disk 50 rotates, the cam surface 104 will be brought into engagement with the roller 103 on the rocking lever 99, causing the chamber to be closed to the atmosphere and open to the exhausting device through the medium of the rod 98. As soon as the valve is closed the exhausting apparatus beginning in operation, creates a vacuum in the vacuum chamber, and thereby creates a vacuum in the receptacle which is being sealed. The rotation of disk 50 at the same time causes the slide rod 41 to raise through the medium of block 46^a, roller 52, and cam groove 49 in disk 50, until the jar or receptacle has been brought into contact with the cap, when the rod may continue its upward movement, but the table 42 will be held stationary through the medium of the spring 47 which will be compressed. During the exhausting of the chamber or the creating of a vacuum therein, I prevent the cap on the receptacle from being displaced by the freely sliding weighted rod 82. If the formation of the vacuum be too sudden or if suitable restraining means is not used, the cap will be violently lifted and the contents of the container sucked out into the chamber. Heretofore this has often hap-

pened in the packing under vacuum of peanut butter and the like; but the action of the weighted rod 82 is such as to prevent the too sudden lifting of the cap while at the same time it permits of sufficient movement to allow the air to be drawn from the container. After the table 42 is raised, and the vacuum is created in the vacuum chamber, cam 54 operating through the medium of the roller 55 causes the rods 57, 58 and 59 to be moved downward, thus raising the vertical moving arms 92 by the yoke 62, rocking lever 63 and arms 65. This movement of the vertically moving arms 92 in an upward direction draws up with it the movable head 88 through the medium of the pins 91, causing the segmental jaws by reason of their beveled shoulder 84 engaging with the bearing surface 90 to move inward so that the shoulder 86 comes under the lower side of the beading on the cap, and a continued upward movement causes the shoulder 86 to compress the beading between the downwardly extending flange 79 on the centering cap, and the shoulder 86 on the segmental jaws, thus squeezing a part of the packing out of the beading against the outer wall of the receptacle, and creating a mechanical seal, while at the same time retaining the vacuum in the receptacle. A further rotation of the shaft 37 causes the roller 56 to engage with the cam 53, which causes the rods 57, 58 and 59 to raise, thereby lowering the vertical moving rods 92 through the medium of the rocking arm 63 and lever 65 causing the head 88 to lower, and the segmental jaws by means of the springs 89 are forced outward and away from the under side of the beading. As soon as the segmental jaws are out of engagement with the beading, the roller 103 disengages with the cam surface 104 on the disk 50, causing the spring 101 to rock the rocking lever 99, so as to draw the rod 98 downward, thus rotating the disk of the valve 97 and opening the same to atmosphere, thereby allowing the pressure in the chamber 4 to rise to the pressure of the atmosphere. At the same time that the valve is being opened, the table 42 through the medium of the slide rod 41, roller 52 and cam groove 49 is being lowered. The operator having withdrawn pressure from the treadle 15, the spring 33 drawing upward on the same, causes the pin 21 having a beveled surface 23 to engage with the slide bolt 26 in the clutch, thereby throwing the clutch out of engagement while the brake 39 stops the rotation of same. As soon as the atmosphere passes into the chamber, the door 5 opens by gravity leaving the machine in its normal position as shown, permitting access to the chamber 4, and the removal of the receptacle, having a cap sealed thereon by the pressure of the atmosphere and by mechanical means.

It will be noted that this mechanism provides for a mechanical seal in which the sealing dies and abutment are closely associated with each other forming a sealing mechanism with balanced forces. With this form of sealing device the container is not required to act as the abutment or to receive the thrust of the sealing mechanism. This is of great importance in vacuum sealing machines as the breakage of a container in these machines causes the immediate flooding of the vacuum chamber with the contents of the package, which are usually liquid. For the same reason, where power is used to effect the sealing operation, it must be applied in such a manner that no breakage results from its application and the mechanism described achieves this purpose.

What I claim and desire to secure by Letters Patent is:—

1. In a vacuum sealing machine, the combination with a chamber and its closure, of a sealing device located within the chamber, and a self-adjusting support for the container having its moving parts within the chamber.

2. In a vacuum sealing machine, the combination with a chamber having a part thereof in the form of a movable closure whereby the chamber may be opened or may be hermetically sealed, of a power driven sealing device adapted to operate upon a container within said chamber, a support for the container, and a pedal mechanism adapted to operate the said movable closure and to control the operation of the sealing device.

3. In a vacuum sealing machine, the combination with a chamber having a part thereof in the form of a movable closure whereby the chamber may be opened or may be hermetically sealed, of a power driven sealing device adapted to operate upon a container within said chamber, an abutment adapted to bear upon one end of the container, the said abutment being resilient to compensate for varying sizes of containers, and a pedal mechanism adapted to operate the said movable closure and to control the operation of the sealing device.

4. In a vacuum sealing machine, the combination with a chamber, of a power sealing device located within the chamber, a support for the container, a closure for the chamber, and a pedal adapted to operate the closure and to control the operation of the sealing device.

5. In a vacuum sealing machine, the combination with a chamber, of a power sealing device located within the chamber, a self-adjusting support adapted to present varying sizes of containers to the sealing device, a closure for the chamber, and a pedal adapted to operate the closure and to control the operation of the sealing device.

6. In a vacuum sealing machine, the combination with a chamber having a part thereof in the form of a movable closure whereby the chamber may be opened or may be hermetically sealed, of a power driven sealing device adapted to operate upon a container within said chamber, a continuously running power shaft, a clutch intermediate the said shaft and said sealing device, and a pedal mechanism adapted to operate the said closure and to control the action of said clutch.

7. In a vacuum sealing machine, the combination with a chamber, of a power operated sealing device located within the chamber, a power operated container support equipped with self-adjusting devices adapted to compensate for varying sizes of containers, a closure for the chamber, and a pedal adapted to operate the closure and to control the operation of the sealing device and the container support.

8. In a vacuum sealing machine, the combination with a chamber, of a power operated mechanical sealing device located within the chamber, a self-adjusting support adapted to present varying sizes of containers to the sealing device, a closure for the chamber having a movement independent of the adjusting movement of the support, and a pedal adapted to operate the said closure and to control the operation of the sealing device.

9. In a vacuum sealing machine, the combination with a chamber, of a power operated mechanical sealing device located within the chamber, a power operated container support equipped with self-adjusting devices to compensate for varying sizes of containers, a closure for the chamber having a movement independent of the movement of said devices, and a pedal adapted to operate the said closure and to control the operation of the sealing device and the said support.

10. In a vacuum sealing machine, the combination with a chamber, of a power operated sealing device located within the chamber and adapted to effect a mechanical seal with a container without imposing a thrust thereon, a self-adjusting support adapted to register varying sizes of containers with the said sealing device, a closure for the chamber, and a pedal mechanism adapted to operate the said closure and to control the operation of the sealing device.

11. In a vacuum sealing machine, the combination with a chamber and its closure, of a power operated sealing device located within the chamber and adapted to effect a mechanical seal with a container without imposing a thrust thereon, a pedal mechanism adapted to operate the closure and to control the operation of the power sealing device, and a self-adjusting support located

- within the closed chamber and adapted to present varying sizes of containers to the sealing device.
12. In a vacuum sealing machine, the combination with a chamber, of a power operated mechanical sealing device located within the chamber, means for supporting the container and effecting a closure of the chamber, and a pedal mechanism adapted to operate the closure means and to control the operation of the sealing device.
13. In a vacuum sealing machine, the combination with a chamber, of a sealing device located within the chamber, a support for the container, a closure for the chamber, and a device adapted to regulate the lifting of the container cap during the exhausting operation.
14. In a vacuum sealing machine, a casing comprising a chamber having a side opening, a closure for sealing the chamber, a lever attached to the closure and adapted to support and to move the same; operating means for the lever, and a second lever attached to the closure in offset relation to the first lever and adapted to control the general position of the closure during its movement by the first lever, the combined action of the levers operating to maintain the closure in a parallel relation to the side opening.
15. In a vacuum sealing machine, a casing comprising a chamber having a side opening, a closure for sealing the chamber, means for supporting the closure and for moving it laterally to and from the said opening, in combination with a lever operating on the closure to maintain it in substantially parallel relationship with the walls of said opening during the movements of the said closure.
16. In a vacuum sealing machine, a casing comprising a chamber having a side opening, a closure for sealing the chamber, a yoked lever for supporting and moving the closure, and a second lever attached to the closure and adapted to determine the position of the closure relatively to the said yoked lever.
17. In a vacuum sealing machine, a chamber having an opening, a closure for the chamber, packing interposed between the chamber and the closure, and a resilient device adapted to check the movement of the closure in the operation of sealing the chamber and to facilitate the movement in the operation of unsealing.
18. A sealing chuck comprising a head having a depending annular jaw adapted to contact with the upper part of the cap flange, the said jaw having a beading adapted to impress an annular groove in the upper part of the cap flange, a series of radially movable sectional jaws adapted to contact with the under part of the cap flange, a support for the sectional jaws, and means to cause a relative movement of the head and the sectional jaws whereby the cap flange is compressed in a vertical direction.
19. A sealing chuck comprising a head having a recess to receive the body of the cap and an annular jaw adapted to contact with the upper part of the cap flange, the said annular jaw being formed with a beading adapted to impress an annular groove in the upper part of the cap flange, a series of radially movable sectional jaws adapted to contact with the under part of the cap flange, a support for the sectional jaws, and means to cause a relative movement of the head and the sectional jaws whereby the cap flange is compressed in a vertical direction.
20. A sealing chuck comprising a head having an annular jaw adapted to contact with the upper part of the cap flange, the said jaw having a beading adapted to impress an annular groove in the upper part of the cap flange, a support, a series of sectional jaws pivoted to said support and adapted to contact with the under part of the cap flange, the said sectional jaws being radially movable to and from the cap flange, and means to cause a relative movement of the head and the sectional jaws and support whereby the cap flange is compressed in a vertical direction.
21. In a vacuum sealing machine, the combination with a chamber having a part thereof in the form of a movable closure whereby the chamber may be opened or may be hermetically sealed, of a power driven sealing device adapted to operate upon a container within said chamber, a continuously running power shaft, a clutch intermediate said shaft and said sealing device, an exhausting connection for said chamber, a valve controlling said connection, and a pedal mechanism adapted to operate directly the said closure and to control the action of said clutch and said valve.

In testimony whereof, I have signed my name to this specification, in the presence of two subscribing witnesses.

JOSEPH V. HULL.
